UNITED STATES PATENT OFFICE.

CHARLES A. RIGHTER, OF PHILADELPHIA, PENNSYLVANIA, ASSIGNOR TO DORNAN BROS. & CO., OF SAME PLACE.

DESIGN FOR CARPETS.

Specification forming part of Design No. 8,928, dated January 25, 1876; application filed January 15, 1876.
[Term of Patent 3½ years.]

To all whom it may concern:

Be it known that I, CHARLES A. RIGHTER, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

I claim as my invention—
The configuration of the design hereunto annexed, when applied to carpeting.

CHAS. A. RIGHTER.
